(57) **CLAIM**

The ornamental design for a mug press, as shown and described.

DESCRIPTION

FIG. 1 is a front, left, top isometric view of an embodiment of a mug press;

FIG. 2 is a rear, right, top isometric view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is bottom plan view thereof.

The broken dash lines shown in the drawings indicate portions of the mug press that form no part of the claimed design.
